LOCOMOTIVE FIRE BOX EQUIPMENT

Herbert W. Snyder, Lima, Ohio

Application March 5, 1934, Serial No. 713,966

24 Claims. (Cl. 110—57)

This invention relates to fire-box or furnace equipment, which, while adaptable to various fields, is especially advantageous and suitable for use on locomotives. More particularly the invention has reference to the provision of means for preheating combustion air, the said means being constructed and arranged in accordance with the following specification in a manner to attain a number of objects and advantages, some 10 of the more important of which are discussed just below.

This invention contemplates the preheating of combustion air and delivering such air through the fire bed supported by the grates at the bottom 15 of the fire-box. The preferred form of air pre-heater equipment employed in accordance with this invention is arranged to utilize a source of exhaust steam on the locomotive, usually the cylinders, as the heating medium during at least 20 a portion of the time the equipment is in operation.

Still further the invention has in view employing exhaust steam from the cylinders of the locomotive when the engine is working, and then 25 switching to a different source of heating medium during periods when the engine is not working.

The invention therefore contemplates a material increase in efficiency of operation, especially from the standpoint of fuel consumption, and 30 I have found that even though exhaust steam from the cylinders is only intermittently available, yet when the arrangements of this invention are employed, including the air heater structure to be described more fully hereinafter, a drop in fuel consumption of from 8 to 9% and even higher may be obtained.

The invention is also concerned with a problem relating rather to maintenance of equipment than to efficiency of combustion, which 40 problem can probably be understood to better advantage after a consideration of some of the structural and operating conditions of modern locomotive practice.

With the increase in size, weight and power 45 of locomotives, the fire-boxes, of course, are correspondingly increased in size. These large boxes also require side sheets of great length. The side sheets, each of which is normally formed of a single metal sheet, have been subject to cracking and warping, particularly in the larger locomotives, with the result that considerable difficulty and expense has been encountered in replacements or repairs. Apparently, the cracking and warping has been due primarily to 50 irregular thermal expansion and contraction in

different portions or areas of the side sheets. I have found that the irregularities in expansion and contraction are ordinarily caused by admission of air to the fire-box at different temperatures in different regions thereof, especially 5 during idle periods of the locomotive. In such idle periods, the fire bed frequently develops thin or relatively dead spots and these often appear along the sides of the fire-box adjacent to the side sheets. As a result considerable quantities of relatively cold air have been admitted 10 from time to time through these thin or dead spots and this has caused irregularities in the temperatures to which the side sheets are subjected. In consequence, of course, the side sheets 15 expand and contract in a similarly irregular manner. Furthermore, in ordinary locomotive practice, especially as contrasted with stationary power plant operation, the temperature of the air admitted through the fuel bed even under 20 normal conditions varies over a wide range, since the air is directly admitted at the outside atmospheric temperature which may be, for example, —20° F. or +100° F.

The present invention at least in large part 25 overcomes the foregoing difficulties and obtains more uniform and more efficient combustion, by providing for the admission, with the fuel or through the fire bed, of air which is of approximately uniform preheated temperature under all 30 normal operating conditions; also when the locomotive is standing idle or is drifting, as well as when it is running under power.

A more specific object of the invention is the 35 provision of a novel preheater arrangement including heater elements which are mounted in the air intake openings of the ash pan, preferably along one or more lower edges of the fire-box below the grates.

Another object involves a novel construction 40 and arrangement of heater elements for the purpose of providing a high degree of efficiency in heat transfer. At the same time, these elements are further constructed and disposed in a way to prevent hot coals from dropping out of the ash 45 pan through the air intake openings, this being of importance in avoiding fires.

The invention is also of advantage in providing 50 a system for supplying and controlling the heating medium used in the preheater elements, which system is arranged so that these elements employ exhaust steam derived from auxiliaries or the cylinders or both, when the auxiliaries or the cylinders are working, and from the steam space of the boiler when the auxiliaries or cylinders are 55

not working or do not provide a sufficient supply of exhaust steam.

Still further the present arrangement contemplates automatic valve controlling mechanism 5 providing for the change over from exhaust steam to live steam upon stopping the locomotive and an opposite change when the locomotive is started after a period of idleness.

The manner in which the foregoing objects and 10 advantages are secured, together with others which will occur to those skilled in the art, will appear more fully from a consideration of the following description making reference to the accompanying drawings, in which—

15 Figure 1 is a somewhat diagrammatic side elevational view of a locomotive, with the air pre-heater arrangement of the present invention applied to the fire-box thereof;

20 Figure 2 is a view similar to Figure 1 showing a modified system for control and supply of the heating medium;

25 Figure 3 is a side elevational view on a considerably enlarged scale of a portion of a fire-box with part of the mechanism of this invention applied;

30 Figure 4 is a transverse sectional view of the structure appearing in Figure 3, the section being taken through different parts of the heater mechanism at opposite sides of the fire-box, in accordance with section lines 4a—4a and 4b—4b appearing on Figure 3;

35 Figure 5 is a still further enlarged fragmentary sectional view of certain heater parts taken substantially as indicated by the line 5—5 on Figure 4, with portions omitted for the sake of clarity;

Figure 6 is a fragmentary view illustrating a modified control system for the heating medium;

40 Figure 7 is a sectional view of a valve mechanism employed in the control system of Figure 2; and

Figure 8 is a sectional view of one of the valve devices employed in accordance with the arrangement of Figure 1.

45 In the general layouts of Figures 1 and 2, the locomotive boiler is designated by the letter A, the cab at B, the fire-box at C, the main driving cylinders at D and the tender at E. Furthermore, in these views the letter F indicates, in general, the heater elements which are applied along the 50 lower edge of the fire-box at each side of the locomotive.

55 Before considering the construction, mounting arrangements and operation of the air preheater elements, attention is called to the control and supply system for the heating medium, as employed in Figure 1. From inspection of this view it will be seen that the throttle lever 9 which is pivotally mounted as at 10 is coupled with the throttle rod 11 extending forwardly for connection 60 with the throttle, as by means of the actuating arm 12. The steam supply pipe to the heater elements is shown at 13 and is provided with a manual shut-off valve 14 in advance of which the supply pipe is divided into two branches 65 13a and 13b. The latter of these branches is extended forwardly to communicate with the exhaust cavity or passage of the cylinder or cylinders D. Branch 13a is extended to some source of live steam such as the turret 15 and controlled 70 by a manual shut-off valve 16. This branch is also provided with a valve device 17 which is controlled by the actuating lever 18, connected with the throttle rod 11 by link 19 and the attachment device 20.

75 In accordance with this arrangement when the

locomotive is in operation, the exhaust steam of the cylinders, passing rearwardly through branch 13b, is employed as the heating medium in the heater elements F. Valve 17 is coupled with the throttle control, as by connection with the throttle rod 11 in the manner referred to above, and this valve serves to open the branch 13a when the main throttle is closed by the lever 9 at which time steam is no longer available in the exhaust cavities of the cylinders D.

10 The construction and operation of valve 17 will be apparent from inspection of Figure 8 in which it will be seen that the operating arm 18 is pivotally mounted on the valve casing at 21. The lower end of this arm is adapted to 15 contact with the push rod 22 constituting the stem of valve 23. Valve 23 closes the port between chambers 24 and 25, the former of which is connected by the upper portion of branch 13a with the turret 15 and the latter of which is 20 connected by the lower portion of branch 13a with the supply pipe 13 extended to the heater. The steam pressure from turret 15, therefore, serves to urge the valve toward its closed position and in addition this action may be supplemented by a spring 26.

25 In the preferred adjustment and arrangement of the valve 17 and the connections extended to the throttle lever 11, the valve is opened by the final closing movement of the throttle lever 9 30 and, in view thereof, just as soon as the main throttle of the locomotive is closed, at which time the exhaust steam supply ceases, the heater elements are provided with their heating medium from the turret 15, it being understood, of course, 35 that this latter steam supply may be obtained from any desired source on the locomotive. To ensure the above operation, a gap is preferably left between valve stem 22 (Fig. 8) and lever 18, when the locomotive throttle is in the wide open 40 position.

With a view to preventing flow of steam from the turret to the exhaust passages of the cylinders through branch 13b, I preferably employ a check valve in line 13b which is indicated at 27 in 45 Figure 1. It will thus also be seen that I have provided (in the valve 27) an automatic means of closing the exhaust steam line when the locomotive cylinders are not working.

50 With further reference to the general layout of Figure 1, the exhaust from the heater F may be discharged directly to the track or, as shown in the drawings, the exhaust may be delivered through pipe 28 into a steam trap 29 after which the condensate may be conducted through connection 30 provided with check valve 31 to the water space of the tender E by any suitable or desired means. The exhaust and condensate arrangements shown in Figure 2 are the same as those just mentioned.

55 Turning now to the control and supply system for the heater, as incorporated in the modification of Figure 2, the supply pipe 13 with its shut-off 14 is again employed and this pipe again branches as shown at 13a and 13b, the latter 60 branch being extended to the cylinder exhaust. In this instance, however, branch 13a connects with valve 32 with which pipes 33 and 34 also communicate. Pipe 33 is extended to the turret 15 or other suitable live steam source and may be 65 provided with a shut-off valve 16 as in Figure 1. The forwardly extending connection 34 preferably communicates with the main steam supply to the cylinders D beyond the main throttle. For 70 example, this connection 34 may be coupled with 75

the steam pipe a portion of which is shown at 35 in Figure 2. Pipe 34, therefore, will carry pressure only when the main throttle is open; and the valve 32 is of the type which, in the absence of pressure in line 34, opens communication from pipe 33 to the branch 13a and closes this communication upon the admission of pressure from pipe 34.

While valves of several different types might 10 possibly be employed for the purpose, I prefer to use the valve device illustrated in Figure 7 in which it will be seen that the pipe 33 may be coupled with pipe 13a when the valve 32a is unseated. It will be noted that valve 32a is so 15 positioned with respect to its seat that, in the absence of pressure in connection 34, the pressure in line 33 will open the valve and thus establish communication through the valve housing to branch pipe 13a. On the other hand, when 20 the pressure in line 34 rises appreciably, as when the main throttle of the locomotive is opened, this pressure, acting on the valve elements 32b and 32c, carries the valve to a position in which the valve element 32a closes its seat.

With further reference to this valve device, it 25 should be noted that the valve part 32b closes communication between the pipe 34 and the live steam passage to which pipe 13a is coupled and thus prevents flow of steam from the dry pipe 30 into the air preheater elements. When the valve is in the right-hand position, i. e., when the valve element 32a is unseated, the portion 32c serves to close the chamber with which pipe 34 connects.

It will be seen, therefore, that this system automatically 35 shifts the steam source employed in the air heater from the exhaust steam of the cylinders D to the live steam of the turret 15, the latter, of course, being employed when the throttle lever 9 is closed and the pressure, therefore, 40 reduced in the dry pipe 35. In the scheme of Figure 2 a check valve 27 also appears in the forwardly extending branch 13b, this being for the purposes already mentioned.

With respect to the showing of both of the arrangements described, it might be noted that the 45 throttle lever in each of Figures 1 and 2 is illustrated in open position. Valve 17 of the arrangement of Figure 1, (shown in detail in Fig. 8) is, therefore, in closed position. Still further, both 50 systems contemplate the use of a blower fitting 36 interposed in the supply line extended from the turret 15 beyond the shut-off valve 16 therein, this fitting being provided for the purpose of admitting steam to the heater F from some source 55 not carried on the locomotive, as in a roundhouse when the locomotive is being fired. A pressure reducing valve 31 may also be employed and this is desirably positioned beyond the fitting 36 so 60 that excessive pressure may not reach the heater elements either from the turret 15 or from some external source. In addition, this pressure reducing valve is of especial advantage in the control system of Figure 2 since a reduced pressure 65 to the left of valve 32a appearing in Figure 7 is desirable in ensuring proper operation of the valve mechanism 32 under the influence of pressure admitted on the right-hand side 32c of the valve 32b, through the pipe 34. For a similar purpose, 70 the valve parts 32b and 32c may be made of larger diameter than the valve part 32a.

With a view to positively preventing entrance 75 of steam into the air heater elements at full boiler pressure, the systems of Figure 1 and Figure 2, as well as of Figure 6 to be described hereinafter,

contemplate the use of a safety valve 64 in the supply pipe 13, as shown.

With regard to the control system of Figure 1, it might be mentioned that this arrangement is of 5 advantage in providing a positive mechanical means of closing the steam supply line from the turret to the heater when the main throttle is opened; and vice versa. This particular arrangement is well adapted to locomotives having an 10 external throttle rod connection to the main 15 throttle. On the other hand, the system of Figure 2 is particularly adapted to locomotives in which an internal throttle connection is employed. Furthermore, the scheme of Figure 2 provides an 15 entirely automatic means of controlling the supplemental steam supply from the turret, this being accomplished by the valve device 32 which is under the influence of pressure in the main steam supply pipe extended to a cylinder or cylinders.

The still further modified layout of Figure 6 20 is of advantage for a number of reasons including its simplicity and the fact that, according to this scheme, if it be desired to supplement the exhaust steam available with steam from the turret, this may be done by opening the manual valve 65. 25 This valve 65 is positioned for convenient access in the cab of the locomotive and replaces the valve device 17 of Figure 1 and the valve device 32 of Figure 2, as will readily be apparent from inspection of Figure 6. The system of Figure 6, of 30 course, also contemplates the employment of a blower fitting 36 and a reducing valve 31.

The arrangement and structure of the air heater elements appears in greater detail in Figures 3 to 5 inclusive, but before discussing the structure 35 it might first be mentioned that in accordance with this invention it is of importance to arrange the heater equipment so as to deliver the pre-heated combustion air upwardly through the grates and the fire bed. With this in mind, as 40 shown in Figures 1 and 2 the heaters or heater assemblies are arranged at the lower edges of the fire-box. In the side elevation and transverse section of Figures 3 and 4, respectively, a number of features of the supporting arrangement for 45 the heater are illustrated. In these views the numeral 38 indicates the upper and gradually sloped portion of an ash pan, while 39 designates a lower part thereof which is normally provided with an ash door. Furthermore, as best seen in 50 Figure 4, the ash pan and the heater devices F are preferably supported in association with each other as by means of the brackets or the like 40 which extend upwardly from the heaters inside of the side sheets 41 adjacent to the mud ring 42. 55 The elements 40 may be employed to position the side grate rails 43 as clearly shown. Additional support members 44 are arranged at the ends of the heaters, these being bolted to brackets 45 depending from the mud ring and having upwardly projecting elements 40 which also engage the side grate rails. The center or intermediate grate rails may be supported by means of brackets such as that shown at 66 toward the right of Figure 4. This bracket is carried on the top of the 65 main frame cradle and projects up through the ash pan to provide pivotal support for an additional member 67 which, as shown, is grooved or forked to embrace a center rail.

The ash pan may receive at least part of its 70 support by the flanged portions 38a which may be attached to the heaters at the points shown in Fig. 4.

Although, insofar as many features of the invention are concerned, the heaters themselves 75

may take a variety of forms, yet I prefer the arrangement illustrated in the drawings. This construction is of a sectional type, there being two heater sections 46, 46a shown in Figures 1, 2 and 3 which are mounted in end to end relation with an ash pan investigation or clean-out box 47 interposed therebetween. As appears to best advantage in Figures 3, 4 and 5, the heater sections are each comprised of a casing 48 containing a multiplicity of tubes 49 which are preferably of the finned type. These tubes are located relatively close together, and preferably in staggered fashion as appears at the left of Fig. 4 so as to provide maximum efficiency in heat transfer. The tubes extend lengthwise through the heater section and terminate in tube sheets 50 one of which appears in Fig. 5. It will also be seen that the fins lie in planes paralleling the general path of the air in flowing through openings 51 and 52 into the heater and therethrough to be discharged just below the grate through apertures 53 (see Fig. 4).

In addition to the above I have found that the use of finned tubes, especially in substantially the arrangement illustrated, constitutes a very effective means of preventing hot coals from falling out of the ash pan through the intake openings thereof. This is of importance in eliminating a fire hazard which has heretofore been rather troublesome.

While separate steam supply and exhaust or condensate connections may be employed for each heater section, in the form of construction illustrated in the drawings the heating medium is introduced into the tubes 49 by means of a header 54 which is arranged at one end of one of the heater sections. At the other end of this section the tubes 49 discharge into a header chamber 55 which is formed as a part of the central box 47 provided for access to the ash pan. In Figures 3 and 4 it will be seen that this box is provided with a horizontal partition 56 below which a passage 57 is formed for the purpose of conducting steam from the header chamber 55 to the additional header chamber 58 serving as the inlet header for the tubes 49 of the second heater section 46a. Above the partition 56 is an additional chamber or passage 59 normally closed by the ash pan door 60 pivotally mounted at 61 so as to facilitate investigation or cleaning the ash pan.

At the discharge end of the heater section 46a an additional header 62 is provided and this, of course, delivers into the condensate or exhaust pipe 28 hereinbefore mentioned.

The type of heater mechanism described just above is of considerable importance for a number of reasons including the fact that the sectionalized construction is very flexible and readily adapted to a variety of conditions encountered in installation. The sectionalizing of the heater elements themselves permits use thereof at different edges of the fire-box and also facilitates making installations where different numbers of the sections are necessary at different sides of the box. It will also be observed that the heater sections, as well as at least some of the headers, are invertible or interchangeable which, of course, provides even more flexibility and permits making installations with a minimum number of different parts.

In connection with the air preheater and ash pan arrangements generally, it is pointed out that the positioning and mounting of these parts is all worked out with a view to preventing, as

far as possible, the access of air to the fire bed except through the heater elements. With this object in view the arrangement of the grates in the fire-box and the support thereof, especially the support of the side and intermediate rails, has been worked out so as to eliminate, as far as possible, apertures through or around the ash pan and in this way to reduce to a minimum the amount of air which may enter the fire-box except through the heater elements.

While the heater units may be variously disposed with relation to the sides, front, or rear of the fire-box, the disposition shown in Figures 1, 2 and 6, that is, closely paralleling the adjacent side edges of the mud ring and ash pan, is especially desirable, for several reasons, including the following: first, for clearance purposes, since this location interferes least with other parts of the locomotive; second, for inspection and replacement purposes, as is evident from the previous discussion; third, for mounting and supporting purposes, as is also now clear; fourth, for structural purposes, since the air is directly admitted through the heater into the space beneath the grates, with no extended air conduits and with a minimum of change of existing locomotive structure; and fifth, for operational purposes, since this location results in an inclined disposition of the heater tubes, which, in conjunction with the illustrated location of the steam inlet and condensate outlet connections, results in a natural downward flow of the condensate in the tubes.

From the foregoing it will be seen that in one of its broader aspects the invention relates to a power plant layout including a steam generator with its furnace or fire-box and an intermittently operated steam consuming mechanism and provides, in such a layout, a means for pre-heating air admitted to the furnace which means employs, as a heating medium, the exhaust from the intermittently operated engine or the like.

Additionally, the arrangements of this invention provide for introduction of substantially uniformly preheated air to the fire-box even though the preheater equipment operates in part on the exhaust from the intermittently operated mechanism, the heating medium being provided from some other source during those periods when the said mechanism is not working steam.

As brought out hereinbefore, it is of especial importance to ensure admission of preheated air during periods of idleness or periods when the main cylinders are not receiving steam, and the invention is also of especial advantage in meeting this condition since it incorporates means providing for the preheating of the air at the time when there is the greatest danger of irregular expansion and contraction of the side sheets and therefore of cracking or warping of these sheets.

It will also be apparent from the foregoing description and the drawings that the supply and control system for the steam employed in the heaters is of relatively simple construction and yet positive action. The control systems are also advantageous in being entirely or at least largely automatic and this is of importance in avoiding multiplication of the controls which must be attended by the engine crew.

I claim:—

1. In a steam locomotive having a fire-box or the like for combustion of fuel, means for supporting a fuel bed for combustion therein, means for preheating the combustion air supplied to the fuel bed including heater elements, a source of

supply of a heating medium, conduit means for delivering the heating medium from said source to the heater elements, and control means automatically operative upon stopping the locomotive to open said conduit means.

5 2. In a locomotive having a furnace for its boiler, driving cylinders and steam control means for the latter, a mechanism for heating the combustion air for the furnace including heater elements having air passages therethrough delivering into the furnace, conduit means for supplying a heating medium to the heater elements, a valve for controlling flow in the conduit means, and valve operating means connected with the 10 steam control means for the driving cylinders in such manner as to open said valve upon shutting off of the steam to the driving cylinders.

15 3. In combination with the fire-box and boiler of a locomotive, an ash pan below the fire-box, air passages adjacent said pan along the lateral edges thereof for admitting air into the fire-box, heat transfer elements adjacent and generally paralleling said edges and having conduit means for supplying live steam from the boiler to said 20 elements, and means for controlling the supply of steam to said elements, the fire-box, ash pan and air passages being arranged to provide for the flow of substantially all the combustion air through the said passages transversely across 25 said elements.

30 4. In a steam locomotive having driving cylinders and fire-box, means for supporting a fuel bed in the fire-box, a mechanism for heating air admitted to the fuel bed including air heater elements arranged adjacent the bottom of the box for heating air as it passes to the fuel bed, means for conducting exhaust steam from the cylinders to said heater elements for heating purposes when the locomotive is running, and means for supplying another heating medium to said elements when the locomotive cylinders are not receiving steam.

35 5. In a steam locomotive having driving cylinders and fire-box, means for supporting a fuel bed in the fire-box, a mechanism for heating air admitted to the fuel bed including air heater elements arranged adjacent the bottom of the box for heating air as it passes to the fuel bed, means for conducting exhaust steam from the cylinders to said heater elements for heating purposes when the locomotive is running, and means operative upon cutting off the supply of steam to said cylinders for supplying another heating medium to 40 said elements.

45 6. In a steam locomotive having a boiler and boiler furnace, driving cylinders and steam controlling means for the driving cylinders, grates for supporting a bed of fuel in the furnace, a mechanism for heating air admitted to the fuel bed including heater elements with air passages therethrough delivering to the under side of the grates, means for supplying exhaust steam from said cylinders to said elements for heating purposes, and means operative upon shutting off of 50 the steam supply to said cylinders by said control means for supplying an additional heating medium to the heater elements.

55 7. In a steam locomotive having a boiler and boiler furnace, driving cylinders and steam controlling means for the driving cylinders, grates for supporting a bed of fuel in the furnace, a mechanism for heating air admitted to the fuel bed including heater elements with air passages therethrough delivering to the under side of the 60 grates, means for supplying exhaust steam from 65

said cylinders to said elements for heating purposes, a supply line for an additional heating medium extended from a suitable source to the heater elements, a valve in said line, and controlling means for said valve operatively connected with the steam control means for the driving cylinders and arranged to open said valve upon shutting off of the steam to said cylinders.

70 8. In a locomotive having a fire-box and driving cylinders with main steam passages associated with the cylinders, air heater elements associated with the fire-box and having air passages therethrough discharging the primary air of combustion to the fuel in the fire-box, a source of supply for a heating medium for said elements, a connection between said source and said elements having valve means therein, and means for controlling said valve means operative under the influence of pressure in said main steam passages.

75 9. In a locomotive having a fire-box and driving cylinders with main steam passages associated with the cylinders, air heater elements associated with the fire-box and having air passages therethrough discharging the primary air of combustion to the fuel in the fire-box, a source of supply for a heating medium for said elements, a connection between said source and said elements having valve means therein, and control mechanism for the valve means operative to close the valve means upon a rise in pressure in said 80 steam passages and to open the valve means upon a drop in pressure in said passages.

85 10. In a locomotive having a fire-box and driving cylinders with main steam passages associated with the cylinders, air heater elements associated with the fire-box and having air passages therethrough for delivery of air to the fuel in the fire-box, a source of supply for a heating medium for said elements, a connection between said source and said elements, a connection for conducting exhaust steam from said cylinders to said heater elements, and control means for said connections operatively associated with said main steam passages for opening the connection from said source in the absence of 90 appreciable pressure in the main steam passages and for closing the connection from said source upon a rise in pressure in said main steam passages.

95 11. In a steam locomotive having a fire-box or the like for combustion of fuel, means for supporting a fuel bed for combustion therein, and driving cylinders with main steam passages associated therewith, means for preheating air supplied to the fuel bed including air preheater mechanism, a connection extending from the cylinders for conducting exhaust steam to the heater mechanism for heating purposes, a source of supply of another heating medium, a connection extended from said source to the heater mechanism 100 with control means therefor, and means for preventing flow of heating medium from said source to the cylinders through the connection which extends from the cylinders, when the medium of said source is being employed in the 105 heater mechanism.

12. In a locomotive having a fire-box and driving cylinders with main steam control mechanism therefor including a throttle and its actuating means, means for supporting a fuel bed in the 110 fire-box, air preheater means delivering combustion air to the fuel bed, a source of supply of a heating medium, a connection extended between said source and the heater elements, and controlling means for said connection operatively 115

75

- associated with the actuating means for the throttle.
13. In a locomotive having a fire-box and driving cylinders with main steam control mechanism therefor including a throttle and its actuating means, means for supporting a fuel bed in the fire-box, air preheater means delivering combustion air to the fuel bed, a source of supply of a heating medium, a connection extended between 5 said source and the heater elements, and controlling means for said connection including a valve therein and operating connections for the valve coupled with the actuating means for the throttle.
14. In a locomotive having a fire-box and driving cylinders with main steam control mechanism therefor including a throttle and its actuating means, means for supporting a fuel bed in the fire-box, air preheater means delivering combustion air to the fuel bed, a source of supply 10 of a heating medium, a connection extended between said source and the heater elements, and controlling means for said connection including a valve therein and operating connections for the 15 valve coupled with the actuating means for the throttle, the operating connections and said valve being arranged to provide closure of the said connection when the throttle is opened and vice versa.
15. In a locomotive having a fire-box and driving cylinders with main steam control mechanism therefor including a throttle and its actuating means, means for supporting a fuel bed in the fire-box, air preheater means delivering combustion air to the fuel bed, a source of supply 20 of a heating medium, a connection extended between said source and the heater elements, and controlling means for said connection including a valve therein and operating connections for the 25 valve coupled with the actuating means for the throttle, the operating connections and said valve being arranged to provide closure of the said connection when the throttle is opened and vice versa.
16. In a locomotive having a fire-box with means for supporting a fuel bed therein, engine mechanism and steam controlling means for the engine mechanism including a throttle, a mechanism for heating the combustion air supplied to the fuel bed including heater elements with air passages therethrough delivering to the under side of the fuel bed, an exhaust steam passage, means for supplying exhaust steam from said 30 passage to said elements for heating purposes, a supply line for an additional heating medium extending from an additional source to the heater elements, a valve in said line, and controlling means for said valve operative upon actuation of 35 the throttle and arranged to open said valve upon closure of the throttle.
17. In a locomotive having driving cylinders and fire-box with means for supporting a fuel bed therein, a mechanism for preheating combustion air including air heater elements arranged adjacent said means for heating air as it is supplied to the fuel bed, means for conducting exhaust steam from the cylinders to said heater 40 elements for heating purposes when the locomotive is running, conduit means for supplying another heating medium to said elements, and control means for said conduit means automatically operative to open the conduit means when the 45 locomotive cylinders are not receiving steam.
18. In locomotive fire-box equipment having an ash pan with air intake openings along the edges thereof, air preheater mechanism in the intake openings and including tubular heater elements having fins thereon which elements and 5 their fins are so arranged as to provide a multiplicity of relatively small air passages therebetween, whereby to prevent or restrict hot coals or the like from falling out of the ash pan through the intake openings. 50
19. In a locomotive having a boiler, a furnace for the boiler, grates in the furnace for supporting a fuel bed for purposes of combustion, air passages for supplying the air of combustion to the fuel bed through the grates from the under side thereof, and air preheater means extended along a side of the grates in said passages and positioned adjacent to the grates for flow of air transversely therethrough, whereby to discharge 15 preheated air substantially directly to the under side of the grates. 20
20. In combination with a steam generator and an intermittently operating steam motor, apparatus for preheating the air for the combustion in the generator, means for delivering exhaust steam of the motor to said apparatus when the motor is operating, means for delivering steam from the generator to said apparatus when the motor is not operating, mechanism for putting the motor into and out of operation, and means 25 acting under the influence of said mechanism for effecting said change in steam delivery.
21. In a locomotive having a fire-box with grates therein and an ash pan structure therebelow the latter of which is spaced or apertured 30 to provide means for admitting combustion air to the under side of the grates, means for preheating combustion air including tubular heater elements extended along and generally parallel to an edge of the grates associated with an apertured portion of the ash pan, the said tubular elements having fins thereon positioned to provide a multiplicity of passages extended generally transverse the tubular elements from the exterior of the ash pan through the apertured 35 portion thereof to the under side of the grates, and means for supplying a heating medium to said tubular elements. 40
22. In a locomotive having a boiler, a combustion chamber associated with the boiler and an intermittently operated steam motor, means for burning fuel in the combustion chamber, means for preheating air supplied to the fuel for its primary combustion, means for delivering exhaust steam of the motor to the air preheating means 45 when the motor is operating, and means for delivering steam from the boiler to the air preheating means when the motor is not operating, and mechanism for shutting off either of said delivery means when the other is delivering steam. 50
23. In a locomotive having driving cylinders, a boiler and a fire-box with means for burning fuel therein, means for delivering steam from the boiler to said cylinders, preheater means for the air of combustion delivered to the fire-box, a conduit for passing exhaust steam from the cylinders to the preheater to serve as a heating medium therein, a fluid pressure operated valve in said conduit operative to prevent back flow to said cylinders, and means for delivering fluid 55 to said valve to close the same, the last means being automatically operative to deliver fluid to the valve upon closure of the steam delivery means for the cylinders. 60
24. In a locomotive having a boiler, a furnace 65

for the boiler, grates in the furnace for supporting a fuel bed for purposes of combustion, air passages substantially throughout the length of a side edge of the grates for supplying the air of combustion for the fuel bed through the grates from the under side thereof, and air preheater means extended along a side edge of the grates and substantially coextensive in length with said

side edge, the air preheater means being disposed in said passages and positioned adjacent to the grates for flow of air transversely therethrough, whereby to discharge preheated air substantially directly to the under side of the grates substantially throughout the length of the side edge thereof. 5

HERBERT W. SNYDER.
